UNITED STATES PATENT OFFICE.

PAUL SLESAZECK, OF BERLIN-REINICKENDORF, GERMANY.

EXPANDING DEVICE FOR BOILER TUBES AND THE LIKE.

Application filed April 15, 1922. Serial No. 553,221.

To all whom it may concern:

Be it known that I, PAUL SLESAZECK, a citizen of the German Republic, and a resident of Berlin-Reinickendorf, Germany, have invented certain new and useful Improvements in Expanding Devices for Boiler Tubes and the like, of which the following is a specification.

This invention relates to a device for expanding boiler tubes and similar tubes in the walls of boilers, which permits of securing the tubes conveniently and rapidly in a fluid tight manner. In expanding devices at present in use the mandrel, which is adapted to 10 press the expanding rollers radially outwards, is advanced from time to time by a nut. This causes the disadvantage, that the rollers are easily pressed out too far and penetrate into the material too deeply. 15

The feature of the new invention consists in that the casing of the expanding device is split resiliently in its longitudinal direction and surrounds a preferably conical nut with friction, this friction being preferably increased by a ring placed around the casing. 20

In the accompanying drawing Figure 1 shows a section of the casing on the line A—B of Fig. 3, as also an elevation of the mandrel.

Fig. 2 shows an external view of the expanding device, and Fig. 3 is a front elevation seen from the right, while

Fig. 4 represents in external view an especially advantageously operating modification of my improved expanding device.

1 is the casing of the expanding device, which at 2 is provided with the openings, in which the expanding rollers 3 are mounted. 4 is a conical mandrel, which may be fed 40 forwards by means of a screw thread 5, by turning its part 6 by hand or mechanically. 7 is a nut, which surrounds the screw-spindle 5, and which externally is provided with a slight cone 8. A corresponding recess is 45 provided in the casing 1 for this cone.

The casing is provided with a number of slots 9 in its axial direction, so that spring tongues 11 are formed, which surround the cone 8 with a strong spring action.

50 The method of operation will now be as follows:

If the spindle 5 is turned in a given direction, the mandrel 4 will thus be advanced towards the left and thus press the expanding rollers 3 radially outwards, so that they 55 expand the tube to be packed. If the expan-

sion pressure is sufficiently great, the conical nut 7 is pressed out somewhat towards the right, as the pressure of the spring tongues 11 has been overcome. The extent of projection of a few millimeters indicates to the workman that the expansion pressure suffices. It is now only necessary for him to turn the spindle 5 in the opposite direction. The nut 7 then returns wholly into the position of Fig. 1, while at the same time the mandrel 4 moves towards the right so that the expanding rollers also move towards the central axis of the casing and the expanding device can be removed, so as to be inserted into another tube, where the same method of operation is repeated.

For increasing the spring pressure of the tongues 11 a ring 12 may be placed over the tongues as shown in Figs. 1 and 2, which 75 may also be resilient. This ring may be moved in an axial direction and the spring power of the tongues thus varied.

It is of advantage to make the ring 12 resilient in order to prevent a deformation of 80 the parts 11 by means of the sharp edges of said ring, when these parts 11 are spread outwardly by the cone 8. The resilience of the ring 12 is effected by means of a slot 13, cut longitudinally in said ring as shown in 85 Fig. 3.

In the modification shown in Fig. 4 the ring 12 is replaced by a spiral spring 14, which is pushed with strong tension over the parts 11 and is adapted to expand radi- 90 ally.

The advantage of the new device consists in a very rapid method of operation and further in that it is possible to operate uninterruptedly without, as with the older constructions, it being necessary to effect a periodic feed of the spindle 5. The workman needs only to take care that he stops the movement for expansion when the externally conically-shaped nut 7 has the right 95 hand end projected a few millimeters beyond the right hand end of the casing.

Having thus particularly described the nature of my invention, what I claim as new and desire to secure by Letters Patent of the 105 United States is:

1. A device for expanding heating tubes in boiler walls, comprising in combination a casing resiliently split in its longitudinal direction, rollers mounted in said casing so as 110 to be radially movable and adapted to be pressed against the tube wall in order to

expand the same, a conically-shaped mandrel adapted to engage between said rollers and having external screw threads and a nut engaging with said screw threads and being 5 frictionally surrounded by said casing.

2. A device for expanding heating tubes in boiler walls, comprising in combination 10 a casing having an open end resiliently split in its longitudinal direction, rollers mounted in said casing so as to be radially movable and adapted to be pressed against the tube wall in order to expand the same, a conically-shaped mandrel adapted to engage said rollers and having external screw threads 15 and a conically-shaped nut engaging with said screw threads and being frictionally surrounded by a correspondingly shaped part of said casing, the smaller base surface of said nut being turned towards the open 20 end of the casing.

3. A device for expanding heating tubes in boiler walls, comprising in combination a 25 casing having an open end resiliently split in its longitudinal direction, rollers mounted in said casing so as to be radially movable and adapted to be pressed against the tube wall in order to expand the same, a conically-shaped mandrel adapted to engage between said rollers and having external screw 30 threads, a conically-shaped nut engaging

with said screw threads, and being frictionally surrounded by a correspondingly shaped part of said casing, the smaller base surface of said nut being turned towards the open end of the casing and resilient means 35 encircling said casing and being adapted to be expanded radially.

4. A device for expanding heating tubes in boiler walls, comprising in combination a 40 casing having an open end resiliently split in its longitudinal direction, rollers mounted in said casing so as to be radially movable and adapted to be pressed against the tube wall in order to expand the same, a conically-shaped mandrel adapted to engage between 45 said rollers and having external screw threads, a conically-shaped nut engaging with said screw threads and being frictionally surrounded by a correspondingly shaped part of said casing, the smaller base surface 50 of said nut being turned towards the open end of the casing and a spiral spring encircling the resilient end of said casing and being adapted to be expanded radially.

In testimony whereof I affix my signature 55 in presence of two witnesses.

PAUL SLESAZECK.
